CARBURETER.

1,312,749.

Specification of Letters Patent. Patented Aug. 12, 1919.

Original application filed April 16, 1914, Serial No. 832,158. Divided and this application filed April 16, 1914. Serial No. 832,159.

To all whom it may concern:

Be it known that I, CHARLES L. RAYFIELD, a citizen of the United States, and a resident of the city of Chicago, in the county 5 of Cook and State of Illinois, have invented certain new and useful Improvements in Carbureters; and I do hereby declare that the following is a full, clear, and exact description of the same, reference being had to 10 the accompanying drawings and to the numerals of reference marked thereon, which form a part of this specification.

This application is a divisional application of my co-pending application for patent Serial No. 832,158 for Carbureters, executed of even date herewith.

This invention has for its object the provision of means associated with the automatic air inlet valve of a certain type of 20 carbureter for augmenting the pressure in the sources of fuel supply in the carbureter to assist the flow through the various fuel valves, which introduce fuel to carburet the air for combustion purposes.

25 It is an object of this invention to construct a carbureter having an automatic air inlet valve and dash pot associated therewith communicating with the fuel supply, and with an inlet fuel supply valve communicating in said dash pot and adapted to be opened by movement of the air valve.

It is also an object of this invention to 35 construct a carbureter with a fuel supply valve mounted in the air inlet passage of the carbureter and with said valve disposed so as to be opened by an opening of the air inlet valve.

It is also an object of this invention to 40 construct a carbureter having a fuel supply valve mounted in the air inlet passage to the carbureter whereby an opening movement of the automatic air inlet valve serves to open said fuel supply valve, and with pressure augmenting means connected to said 45 air valve to force fuel under pressure through said fuel valve.

It is also an object of this invention to 50 construct in combination with a carbureter, pressure augmenting means associated with the automatic air inlet and with an auxiliary fuel supply valve mounted adjacent thereto and opened thereby, whereby an opening movement of said air valve increases the pressure in the various fuel sup-

ply chambers of the carbureter and forces 55 the fuel through the various fuel valves.

It is also an object of this invention to construct a carbureter wherein a plurality of fuel inlet valves are provided and a plurality of fuel supply chambers, and with a 60 communication between said respective fuel supply chambers to equalize the pressure therein.

It is furthermore an object of this invention to construct a carbureter wherein a 65 plurality of fuel supply valves are provided, each communicating in a different fuel supply chamber, said supply chambers communicating with one another and with means for augmenting the pressure in said 70 fuel supply chambers to force fuel through the respective fuel supply valves.

It is finally an object of this invention to construct a carbureter instantly responsive to a sudden opening movement of the throttle valve to cause a charge of fuel to be introduced into the carbureter affording a rich mixture adapted to accelerate the engine.

The invention (in a preferred form) is 80 illustrated in the drawings and hereinafter more fully described.

In the drawings:

Figure 1 is a front side elevation of a 85 carbureter embodying the principles of my invention.

Fig. 2 is a rear side elevation thereof.

Fig. 3 is a central vertical longitudinal section taken through the carbureter, with parts shown in elevation.

90 Fig. 4 is a fragmentary enlarged detail section taken through the air inlet end of the carbureter.

Fig. 5 is an enlarged detail section of the air-controlled fuel supply valve.

95 Fig. 6 is a section on line 6—6 of Fig. 5.

Fig. 7 is a fragmentary top plan view of a portion of the operating mechanisms of the carbureter.

100 As shown in the drawings:

The carbureter comprises an integral casting affording a float feed chamber 1, and a mixing chamber 2. The casting 1, of the float feed chamber comprises cylindrical side walls and an integral bottom wall 3, having 105 a central or axial downwardly directed tubular boss 4, integral with the bottom thereof and opening upwardly thereinto. Said

boss is closed at its lower end by means of a screw plug 5, threaded thereto and engaging a suitable packing washer 6, between the same and the end of said boss to seal the connection. The cover 7, for the float feed chamber is removably secured thereto and extending axially through said chamber and a suitable central aperture in said cover 7, is a rod 8, of a length to extend into the bore in said boss 4, as shown in Fig. 3, and to normally extend slightly above the cover through an aperture therein. Adjustably but rigidly secured on said rod is a float 9, in the present instance shown as constructed of sheet metal, and having a sleeve 10, extending centrally therethrough, and through which the rod 8, extends. Said float feed chamber is cored from the side adjacent the mixing chamber to afford an inward extension A, of the chamber in the space between the same and said mixing chamber, and, as shown, the casing of the mixing chamber 2, is constructed to afford a similar chamber B, extending over said chamber A, and through the wall of the float feed chamber. The bottom of said chamber A, of the float feed chamber, is provided with an aperture therethrough, and threaded therein at its upper end is a cylindric plug 11, which serves to close the bottom of that portion of the float feed chamber and is provided with a central upwardly opening recess or bore therein, communicating with a restricted central bore extending therethrough, which affords the seat for the inlet needle valve, through which the flow of the hydro-carbon fuel into the float feed chamber is controlled. Said plug is provided on its lower end with a peripheral downwardly extending internally threaded flange 12, and threaded thereinto is a hollow connection 13, having a screen 14, stretched across the top thereof.

The induction pipe 15, whereby the gasoline tank communicates with the float feed chamber, is threaded into said connection 13. The horizontal partition 16, between the extension B, of the mixing chamber and the extension A, of the float feed chamber, forming the bottom of one and the top of the other, is provided with an aperture therethrough and threaded therein in alignment with the corresponding seat in the plug 11, is the tubular nozzle or jet pipe 17, the upper end of which extends above the floor 16, in said extension of the mixing chamber, and the lower end of which extends below said partition 16. Slidably and loosely engaged thereon in the extension A, of the float feed chamber is a sleeve 18, which, near its lower end, is restricted and tapered to a point to afford the valve closure 19, to seat within and to close the induction passage through the plug 11. Said sleeve 18, is provided with apertures 18^a, therein slightly above the bottom of the float feed chamber to admit the fluid from said float chamber thereto, and a peripheral flange 20, is provided on said sleeve intermediate its end as shown in Fig. 3. A weak spring 21, is engaged around said sleeve and bears at its upper end on the wall 16, and at its lower end on said flange to hold the lower needle valve normally closed when the float feed chamber is sufficiently full to support the float.

Removably secured in the float feed chamber on the bottom thereof is a bracket 22, and pivotally engaged thereon is a lever 23, the shorter end of which is yoked to engage around the sleeve below the flange 20, and the longer end of which is provided with an aperture therethrough to receive the rod 8. As shown, a diametrically apertured ball 24, is rigidly secured on said rod 8, and seats on said longer end of the lever 23, to afford a self-adjusting bearing for the float on said lever. Said plug 11, is provided with a passage 25, extending downwardly from its inner end to a passage 26, extending peripherally around the same. A pipe 27, is at one of its ends threaded into said plug 11, and communicates with said passage 26, and at its other end is threaded into the lower end of an extension forming a dash pot 28, of an air inlet valve casing 29, which is threaded on a horizontally directed portion of the inlet to the mixing chamber 2.

Integral with the rear wall of the mixing chamber or in other words directed toward the float feed chamber is a bracket or arm 30, having a cylindric seat in the underside thereof co-axial with the bore of the jet nozzle 17, and engaged therein at its upper end and extending through the top wall 31, of the extension B, of the mixing chamber is a needle valve closure 32, for said jet nozzle 17. A spring 33, engaged in said seat in the arm 30, bears on the upper end of said needle valve to hold the same normally seated.

Journaled in a suitable bearing on the rear wall of the mixing chamber is a transverse shaft 34, and secured thereon and projecting into a slot in the stem of the needle valve closure 32, is a finger 35, which acts with a rotation of said shaft 34, to raise said needle valve closure against the tension of said spring 33. At the upper end of the casing affording the mixing chamber is provided an outwardly extending flange 36, which may be apertured to afford engagement with the manifold pipe leading to the engine. Extending through said mixing chamber is a shaft 37, parallel to shaft 34, above the extension B, of the mixing chamber, and rigidly but adjustably secured thereon is a butterfly valve closure 38. The butterfly valve closure 38, may be slightly cut away on one side thereof in a well-known manner, though not so shown, to afford a sufficient passage for the mixture to the manifold pipe 130

to support combustion when the throttle is substantially closed or at its lowest running adjustment. Secured on the outer end of the shaft 37, is a throttle lever 39, whereby 5 said shaft may be rotated and said butterfly valve adjusted. Also rigidly secured thereon is a rectangular block 40, at the inner side of the throttle lever and slidably and adjustably secured thereon is a cam 41, comprising cam faces arranged approximately 10 at right angles to each other and the corner which would otherwise be formed thereby is cut away to afford a rounded continuation of the cam, as clearly shown in Fig. 1.

15 A screw shaft 42, journaled in the ends of said cam block, is threaded through said block 40, and extending through a notch in the shaft 37, is provided on its outer end with an adjusting head 43, whereby the cam 20 may be shifted on said block 40, with reference to its center of rotation, to-wit the shaft 37.

Loosely engaged on the shaft 34, for adjusting the needle valve closure 32, is a 25 downwardly and forwardly extending arm 44, provided at its forward end with a bearing plate 45, removably secured thereon and contacting beneath said movable cam member 41, and adapted to be thrust downwardly 30 thereby to actuate said lever and the shaft 34, to operate said needle valve. Integral with the arm 44, is a downwardly extending arm 46, provided with a set screw 47, extending therethrough and rearwardly beyond the 35 same.

Rigidly secured on said shaft 34, by means 40 of a bracket arm 48, is a tubular element 49. Journaled in said element is a shaft 49 having rigidly secured on the lower end thereof 45 a cam or eccentric 50, which bears against the rearwardly extended end of the set screw 47, to actuate the shaft 34, when the shaft within said tubular element is rotated. Slight movement of the arm 46, on the shaft 34, is afforded, so that rotation of the cam 50, against the adjusting screw serves to swing the lower end of the sleeve or tubular element 49, forwardly, thereby elevating the finger 55, secured on said shaft on the interior of the carburetor and slightly opening the needle valve closure admitting to the extension B, of the mixing chamber a supply of fuel. Secured upon the upper end of the shaft contained within the tubular element 55 50, is a lever 51, and an actuating rod 52, is connected thereto at the extremity thereof by means of a set screw 53, and said actuating rod 52, extends slidably through a bracket 54, mounted on the cover of the float 60 feed chamber.

Rigidly secured on the end of the shaft 37, at the opposite side of the carburetor is an arm 55, provided with a set screw 56, adapted to engage on a projection or lug 57, on 65 the outer wall of the mixing chamber, as

clearly shown in Fig. 2. As shown, a set screw 58, is employed for engaging said arm 55, on the shaft. Said set screws 56 and 58, afford means for adjusting said arm to limit the degree of closure of the butterfly valve to 70 the required amount to maintain a sufficient supply of mixture to the motor to maintain the combustion at the lowest speed of the motor.

A supply of air is provided for the inlet 75 jet 17, and this is admitted through an inlet port provided in the extension B, of the mixing chamber slightly at the rear thereof, and a peripheral flange or tubular extension 80 59, in the wall of the casing is provided around said port and extends outwardly substantially flush with the side walls of the casing as shown clearly in Fig. 2. The passage therethrough tapers inwardly to 85 conduct the air in a strong inflowing current or jet against the jet of hydro-carbon as it comes from the needle valve, thus spraying and thoroughly vaporizing the same and carrying the same therewith into the mixing chamber 2, beneath the butterfly valve 38. 90 As shown also in Fig. 3, a slight elevation or rib 60, is provided on the floor of the extension B, of the mixing chamber at the point where the same communicates in the 95 main mixing chamber, thereby serving to maintain a thin film or layer of the hydro-carbon fuel on said floor 16, to expose a large surface to vaporization.

Another inlet fuel valve or nozzle is provided within the air inlet casing 29, and this 100 comprises a tubular member 61, which is threaded into the top wall of the dash pot chamber 28, and extends downwardly therethrough communicating therein at its lower end through an apertured plug 62.

A perforated cap 63, is secured around the upper end of said tubular member 61, and slidably mounted therein and through the upper end of a tapered aperture in said tubular member is a tapered valve member 105 64. Said tapered valve closure 64, is held normally in closed position by means of a coiled spiral spring 65, seated on the plug 62, in the lower end of said tubular member, and at its upper end said spring bears against a 110 spider 66, integral with an upwardly extending rod 67, which is rigidly engaged in the lower end of said valve closure 64.

An air inlet port is provided to deliver inflowing air to and across the top of the jet nozzle 63. For this purpose as shown a suitable aperture is provided in the upper wall of the casing 29, and threaded thereto is an outwardly flaring casing 68, affording an inner seat against which a conical disk air inlet valve closure 69, is adapted to rest. An elongated tubular boss 70, is formed axially within said casing 29, and wound therearound and seating at its lower end on said boss is a spiral compression 115 120 125

4
spring 71, which at its upper end seats within a recessed portion of said valve closure 69, to normally hold the same in closed position. A valve stem 72, is rigidly secured in 5 said closure 69, and is slidably mounted within said tubular boss 70, with the lower end of said stem extending into the dash pot chamber 28, and secured on said lower end is a piston 73, adapted to move within said 10 dash pot chamber and apertured to receive the tubular element 61, therethrough.

A contact screw 74, is threaded through one side of said valve closure 69, and is adapted to contact the upper end of said 15 closure 64, to depress the same with a downward or opening movement of said closure 69, and inasmuch as said contact screw is threaded into the aperture 69, it may be adjusted to contact the closure 64, at any 20 predetermined time.

As shown, the outer periphery of said flared casing 68, is fluted, and a spring detent 75, is mounted in an extension 76, formed on said casing 29, to hold said flared 25 adjustable casing 68, in an adjusted position. Of course, when the casing is adjusted inwardly the compression of the spring against the closure 69, is increased thereby, while outward adjustment decreases such 30 pressure, thereby allowing the air inlet valve to open at any desired predetermined draft or difference of pressures.

As shown, a tubular casing or hood 77, closed at its upper end is threaded upon a 35 central raised boss 78, on the cover of the float feed chamber to exclude dust and dirt therefrom. Said boss, as shown, is also provided with a vent passage 79, therethrough from the float feed chamber to vent said 40 chamber against internal pressure. Pivotally engaged in said hood and extending through a slot in the side wall thereof is a bent lever, one arm 80, of which extends over and into position to engage the rod 8, 45 when the float feed chamber is filled to normal capacity. The other arm 81, of said lever extends downwardly on the outer side of said hood and is engaged by a suitable rod to permit manual actuation thereof 50 holding the rod 8, with the float thereon downwardly until the carburetor is slightly flooded to facilitate starting carburation. A spring, 82, is engaged on said lever and acts to hold the arm 80, upwardly out of position 55 out of contact with said rod 8, as clearly shown in Fig. 3. As clearly shown in Fig. 3, the carburetor casing is cored around the mixing chamber to afford an exterior water jacket denoted as a whole by the reference 60 numeral 83, which may be connected to the radiator of the engine if desired. However, such a water jacket may or may not be provided, depending in part on the size of the carburetor, the capacity required and the 65 character or use for which intended.

The operation is as follows:

The carburetor having been assembled and suitably connected with the manifold pipes of the engine, and with the fluid supply pipe from the tank, is adjusted to regulate 70 the air supply through the automatic valve 69, and to regulate the inlet to the needle valve 35, in the extension B of the mixing chamber. The adjustment for said needle valve is effected by shifting the cam 41, relatively to the shaft 37, by means of the screw shaft 42, to vary the degree of opening to the throttle requirement, so that the needle valve will be sufficiently opened to maintain combustion at the lowest engine rate when 80 the butterfly valves in the mixing chambers are approximately closed. A wide range of adjustment is afforded by means of said cam, and practically any inlet requirement can be secured thereby, and when adjusted for the 85 lowest engine rate a further degree of opening of the valve may be secured by means of the cam or eccentric 50, which serves to rotate the shaft 34, slightly in the arm 48, against which said cam acts, thereby permitting the needle valve to be further opened and slightly flooding the carburetor to begin the carburation. This is also facilitated by means of the tickler lever on the float feed chamber whereby the float may be held 90 depressed and the inlet valve 19, held open to permit flooding of the float feed chamber. The automatic air inlet valve of course is adjusted so that normally said valve remains closed. By adjusting the flaring casing for 100 said automatic valve inwardly or outwardly substantially any air inlet requirement for certain differences of pressure may be attained. The adjustment of the needle valve closure 32, within the extension B, of the 105 mixing chamber is such as to maintain a low engine rate of speed, as when the engine is idling, the mixture escaping therefrom from the manifold pipe to the cut away portion in the edge of the butterfly valve closure 38, which is just above the mouth of the extension E, of the mixing chamber, when 110 said butterfly valve is closed. As the throttle valve is opened wider the draft to the engine increases, thereby causing an opening 115 of the automatic air inlet valve and consequently an opening of the fuel supply valve positioned in the inlet casing 29. In each case the air admitted to the carburetor blows directly across the fuel inlet, thereby easily 120 vaporizing the fuel and then passing on into the mixing chamber. A secondary action also takes place with a sudden opening movement of the automatic air inlet valve due to the sudden depression of the piston 53, connected thereon and augmentation of pressure 125 takes place throughout the fuel supply lines of the carburetor, causing the fuel to be forced under pressure through each of the fuel inlet valves so that the engine may be 130

accelerated in instant response to a sudden opening of the throttle valve.

I am aware that various details of construction may be varied through a wide range without departing from the principles of this invention. I therefore do not purpose limiting the patent granted otherwise than necessitated by the prior art.

I claim as my invention:

1. A carbureter comprising a casing affording a float feed chamber, a mixing chamber, jet nozzles therefor adapted to admit hydro-carbon fluid, a throttle valve, means for regulating the inlet from one of the nozzles simultaneously and correspondingly with the adjustment of the throttle valve, ports for admitting air into the mixing chamber across the discharge for the nozzles, an automatically operated normally closed valve, a dash pot connected therewith, said dash pot in communication with the float feed chamber to maintain a supply of fuel in the dash pot, one of said fuel nozzles communicating in said dash pot chamber, a piston movable in said chamber and connected to said air valve to augment the pressure in the fuel supply of the carbureter to force fuel under pressure through said respective jet nozzles, and an uninterrupted closed passage for the mixture flowing from said automatically operated normally closed valve to the throttle valve.

2. In a carbureter of the class described a single butterfly valve controlling the flow of mixture therefrom, an air inlet port at one side of the carbureter, an automatic air inlet valve controlling the admission of air therethrough, a fuel valve mounted adjacent said air valve and adapted to be opened directly different proportionate amounts thereby, a closed passage affording an uninterrupted flow for the mixture formed in said air inlet passage and flowing toward said throttle valve, and a piston connected to said air valve and movable in the source of fuel supply to augment the pressure to force fuel through the supply valve into the carbureter.

3. In a device of the class described a casting, a cylindrical mixing chamber forming a part thereof, said mixing chamber open at its upper end and closed at its lower end, a butterfly throttle valve mounted in said mixing chamber to control the flow therefrom, an air inlet passage communicating laterally

in the lower end of said mixing chamber, an automatic air inlet valve mounted in said passage, a fuel supply valve mounted in said passage adapted to be opened by said air valve, and another fuel supply valve mounted in a normally open air passage and communicating with said mixing chamber to supply a mixture thereto when said automatic air valve is closed.

4. In a device of the class described an air inlet valve mounted in the inlet passage of a carbureter, a dash pot formed on the lower end of said inlet passage, a piston mounted on said air valve and movable in said dash pot, a fuel supply valve communicating in said dash pot chamber adapted to discharge fuel into said air passage, said valve adapted to be opened by said air inlet valve, a mixing chamber in the carbureter with which said air passage communicates, said mixing chamber open at its upper end and closed at its lower end whereby the only air entering the lower end of said carbureter passes by said automatic air inlet valve.

5. In a carbureter of the class described a mixing chamber open at its upper end and closed at its lower end, an air inlet passage communicating in the lower end thereof, an automatic air inlet valve controlling the admission to said passage, a fuel supply valve mounted in said passage adapted to be opened by said air inlet valve, and a dash pot mechanism connected with said air valve to prevent fluttering thereof.

6. In a device of the class described a carbureter having a mixing chamber open at its upper end and closed at its lower end, an air inlet passage communicating laterally in the lower end thereof, a fuel supply valve mounted in said passage, and an automatic air inlet valve offset therefrom and disposed thereabove to control the flow of air through said air inlet passage and to open said fuel valve different proportionate amounts in accordance with the adjustment of said air valve into open position.

In testimony whereof I have hereunto subscribed my name in the presence of two subscribing witnesses.

CHARLES L. RAYFIELD.
